(57) **CLAIM**

The ornamental design for optical network terminal, as shown and described.

DESCRIPTION

FIG. 1 is an isometric view of an optical network terminal showing our new design;

FIG. 2 is a side view thereof;

FIG. 3 is an opposite side view thereof;

FIG. 4 is a front view thereof;

FIG. 5 is a back view thereof;

FIG. 6 is a top view thereof; and,

FIG. 7 is a bottom view thereof.

Portions of FIGS. 1–7 that are shown as broken lines are for illustrative purpose only and form no part of the claimed design.
